UNITED STATES PATENT OFFICE.

STEPHEN RENOVICH, OF NEW YORK, N. Y.

TRAIN-CONTROLLING APPARATUS.

1,333,678.

Specification of Letters Patent. Patented Mar. 16, 1920.

Application filed February 2, 1917. Serial No. 146,154.

To all whom it may concern:

Be it known that I, STEPHEN RENOVICH, a resident of the United States, residing at New York, in the county of New York and State of New York, have invented new and useful Improvements in Train-Controlling Apparatus, of which the following is a specification.

This invention relates to improvements in train controlling apparatus, and has particular application to signal controlled stopping mechanism whereby the propelling power of the motor car may be cut off and the brakes applied in the event of the train running by a danger signal.

In carrying out the present invention, it is my purpose to provide train controlling apparatus of the class described whereby in the event of the train running into a danger zone the propelling power will be cut off through the medium of an electro-responsive device and brake shoes applied to the track rails through the agency of a second electro-responsive device, both of the said devices being under the control of a motor operated switch that is controlled by the block signal, the motor being energized when the signal is at danger and the train attempts to pass such signal.

With the above and other objects in view, the invention consists in the construction, combination and arrangement of parts herein set forth and falling within the scope of the claim.

In the drawings:

Figure 1 represents a side elevation of a locomotive equipped with the apparatus comprised in the present invention.

Fig. 2 is a detail view of the device for cutting off the power of the locomotive under danger conditions.

Fig. 3 is a detail side elevation of the brake shoe and operative mechanism therefor.

Fig. 4 is a sectional side view of the casing inclosing the motor for closing the circuits of the brake operating shoe and throttle closing mechanism, and illustrates the motor and associated elements.

Fig. 5 is a front view of the motor casing, illustrating the arrangement of the contacts.

Fig. 6 is a detail side elevation of the track relay.

Fig. 7 is a diagrammatic view of the application of the invention.

Referring now to the drawings in detail,

1 designates a trackway, while 2 indicates a contact rail arranged between the lines of rails of the trackway. One line of rails of the trackway and the contact rail 2 are divided into sections constituting blocks by means of insulation 3. Arranged at each end of each block is a relay 4, and located at the meeting ends of adjacent blocks is a source of energy as a battery 5. Each relay 6 includes coils 8 and an armature 4', normally held away from the coils by a spring 4" and having one end extended. The extended end of the armature, in the normal position of the relay, is spaced apart from contacts 11, 12 and when the coils of the relay are energized the armature 4' is drawn into engagement with the pole pieces of the coils and the extended end of such armature bridges the contacts 11, 12. One terminal of the coils 8 in each of the adjoining blocks is connected by means of a wire 9 with one side of the battery 5, while the other terminals of the coils of the relays in the adjacent ends of the blocks are connected with 80 the block forming line of rails of the adjoining blocks by means of conductors 10, respectively, while the other side of the battery 5 is connected with the continuous line of rails of the trackway through the medium 85 of a conductor 6. Each contact 12 is connected with the corresponding conductor 9 by means of a wire 14, while each contact 11 is connected with a corresponding block forming section of the contact 2 by means of 90 a wire 7.

By means of this arrangement, it will be seen that when a train enters a block, the wheels and axles bridging the lines of rails of such block will cause the relays in the 95 adjacent blocks to be energized, current for each relay flowing from one side of the particular battery 5 through the conductor 6, the continuous line of rails of the trackway, the wheels and axles of the train in the 100 occupied block, the other block forming section of the lines of rails of the trackway, the conductor 10 connected to such section, the relay coils, and then back to the other side of the battery by way of the conductor 105 9. Upon the energization of each relay the armature 4' is actuated so that the extended end thereof will bridge the contacts 11 and 12, thereby connecting the contact rail to the side of the battery 5 opposite from that 110 side connected to the continuous line of rails, so that the stopping mechanism of the

trains in the adjacent blocks will be energized as hereinafter described.

Depending from the locomotive and arranged above the respective lines of the trackway are substantially U-shaped brackets 15, and fastened to the interconnecting section of each bracket 15, and projecting upwardly therefrom are magnets 16, while slidably mounted in an opening formed in the central section of the bracket between the magnets is a rod 17. Secured to the lower end of the rod 17 is a brake shoe 18, adapted to engage the track rail, while mounted upon the upper end of the arm 17 is an armature 19, disposed within the influence of the poles of the magnets 16. Surrounding the rod 17 between the central section of the bracket and the armature 19 is a coiled expansion spring 20, that acts to hold the armature of the brake shoe in elevated position thereby preventing the brake shoe from contacting with the corresponding line of track rails.

Arranged upon the locomotive adjacent to the throttle valve lever is a throttle valve closing device embodying a cylinder 21, suitably fastened to the cab end of the boiler and projecting outwardly therefrom and a U-shaped guide 22, having the ends of the legs thereof fastened to the outer end of the cylinder 21. Mounted within the cylinder 21 is a piston 23 with a piston rod 24, projecting outwardly through the outer end of the cylinder and through an opening in the interconnecting member of the guide 22. Working in the guide 22 is a cross head 25 that is connected with the rod 24, and forms a bearing therefor, and connected to the outer end of the rod 24 is an armature 26 disposed within the influence of the poles of electromagnets 27 secured to the outer end of the guide 22. Surrounding the rod 24 between the armature 26 and the guide is a coiled expansion spring 28 that acts to hold the armature normally out of engagement with the poles of the magnets. The armature 26 is connected through suitable mechanism with the throttle valve lever so that when the magnets are energized and the armature drawn into engagement with the poles thereof the throttle valve is closed, the piston 23 in the cylinder 21 acting as dash pot to retard the movement of the piston rod so as to prevent the too sudden closing of the valve.

Located within the cab of the locomotive is an electric motor 29, and one side of the motor 29 is grounded upon one of the wheels of the locomotive by a wire 30, while the other side is connected by a wire 31 to a contact wheel 32 depending from the locomotive and bearing upon the contact rail 2. This

motor 29 is mounted within a casing 33 and is connected through the medium of a train of gears 34 with a shaft 35, journaled in suitable bearings carried by the casing 33. Connected with one end of the shaft 35 is an arm 36, and disposed within the path of movement of the arm 36 are pairs of contact fingers 37 and 38, the fingers in each pair being normally spaced apart. One terminal of the magnet 27 is connected with one of the fingers 38, through a wire 39, while the other terminal is connected with a wire 40 which is tapped onto the common wire 31 which is connected with the contact wheel. The magnets 16 are connected in pairs, and one terminal of the same is tapped onto the common wire 31, by means of a wire 41, while the other terminal is connected by means of a wire 42 to one of the fingers of the pair 37. The other two fingers of the pairs 37 and 38 are grounded through the means of a wire 43 upon one of the wheels of the locomotive.

In practice when the train occupies a block and connects the contact rail sections of the adjacent blocks with the respective batteries, a train entering either of the blocks adjacent to the occupied block will be stopped owing to the current flowing from the battery 5 through the motor, thereby operating the arm 36 to close the circuits of the electro-responsive devices controlling the throttle valve and the brake shoes.

While I have herein shown and described the preferred form of my invention by way of illustration, I wish it to be understood that I do not limit or confine myself to the precise details of construction herein shown and described as modification and variation may be made within the scope of the claim and without departing from the spirit of the invention.

I claim:—

An automatic train stop system comprising in combination with a track divided into blocks, a contact rail also divided into blocks, a battery, electromagnets for the blocks connected in pairs so as to act jointly to connect a pair of adjacent block sections to the contact rail, an electrically operated track shoe engaging, when energized, a rail of the track, an electrical device for closing a throttle lever, a contact wheel traveling on the contact rail, a motor having one terminal 105 ground on the engine and the other connected with said wheel, a conductor bridging the track shoe and said device across the terminals of the motor, and a switch arm operated by the motor, for opening and closing said 110 conductor in accordance with the operation of the motor.

In testimony whereof I affix my signature.
STEPHEN RENOVICH.
